UNITED STATES PATENT OFFICE.

JOHN ARMSTRONG ORR, OF WESTONIA, MISSISSIPPI.

BUGGY-TOP.

1,019,692.

Specification of Letters Patent.

Patented Mar. 5, 1912.

Application filed December 1, 1910. Serial No. 595,065.

To all whom it may concern:

Be it known that I, JOHN A. ORR, a citizen of the United States, residing at Westonia, in the county of Hancock and State of Mississippi, have invented certain new and useful Improvements in Buggy-Tops; and I do hereby declare the following to be a full, clear, and exact description of the invention, such as will enable others skilled in the art 10 to which it appertains to make and use the same.

My invention relates to buggy tops.

My principal object is to provide for storing the top when folded so that it will be 15 protected from injury, will be out of the way, and will present a neater appearance.

Another object is to secure better protection for the sides and back of the seat when the top is erected during a storm.

20 Other objects will become apparent from the following description.

The invention consists in the features of construction, combinations and arrangements of parts, hereinafter set forth, illustrated in the accompanying drawing, and more particularly pointed out in the appended claim.

In the accompanying drawing: Figure 1 is a top plan view of a seat having my improved top attached thereto, the top being 30 shown in its folded position. Fig. 2 is a side view of the parts as shown in Fig. 1. Fig. 3 is a similar view with the top raised. Fig. 4 is a cross section, on an enlarged 35 scale, of one of the tubular casings, taken on the line $x-x$ of Fig. 1. Fig. 5 is a cross section on an enlarged scale taken on the line $y-y$ of Fig. 3 and showing the casing open, Fig. 6 is a central longitudinal section of 40 one of the casings on an enlarged scale, and Fig. 7 is a cross section of the back part of the casing on an enlarged scale.

Referring more particularly to the drawing, 1 designates the seat of a buggy, which 45 may be of any ordinary or suitable construction, having a back 2 and sides 3. A tubular casing 4 is fastened to the upper edge of each arm in any suitable manner and extends around back of the seat. The ends of 50 said casing are closed, as at 5. Each of the forward ends of said tubular casing is made in two pieces, the upper half 6 of the cylin-

der being separate from the other portion thereof and constituting the closure therefor. The ends of said closure are fitted in 55 correspondingly shaped grooves 7 in the ends of the casing, as best illustrated in Figs. 4 and 6. Said covers or closures are, therefore, capable of being turned down in a lateral direction to a position outside of the 60 lower portion of the casing, as shown in Fig. 5.

The top proper consists of a series of bows 8 and a covering 9 of chosen material, such as silk or mackintosh. The ends of the bows 65 are pivoted on bolts or pins 10 in the front ends of the tubular casing 4 so that, when they are folded down, their lateral portions are housed in the tubular casings. To the bottom bow there is attached a drop curtain 70 11 conforming to the shape of said bow and of a length to cover the sides and back of the seat. Said drop curtain carries a rod 12 at its lower edge which serves as a weight to hold it down in proper position. It will be 75 understood that the drop curtain is only used when the top is raised, when it can be readily taken out of the tubular casing and arranged so as to protect the sides and back of the seat. When the top is folded, the 80 drop curtain is raised and placed, together with its rod 12, in said casing. When the top is in its folded position, the sliding covers for the forward ends of the tubular casing are raised to closed positions so as to 85 conceal the pivots of the bows and the lateral portions thereof. These portions of the casing then present a very neat appearance and serve as the arms of the seat. In this position, the portion of the top located behind the seat is covered by a curved piece 13 of leather, canvas, or other suitable material. When it is desired to raise the top, the covers of the casing are turned or slid downward 90 into open position, permitting the bows to 95 be readily swung upward. The final operation in adjusting the top over the seat is to lift out the rod 12 and drop the curtain, to which it is attached, down over the sides and back of the seat.

I claim:

In a vehicle, the combination, with a seat and a folding top, of a casing adapted to house the top when folded, laterally sliding

curved covers for the portions of the casing arranged at the sides of the seat, said covers constituting the arms of the seat when closed and adapted to slide below the casing 5 when opened, and a separate cover for the portion of the casing arranged behind the seat.

In testimony whereof, I affix my signature, in presence of two witnesses.

JOHN ARMSTRONG ORR.

Witnesses:

DANIEL CONEY WESTON,
J. W. McCACKEN.
